UNITED STATES PATENT OFFICE.

EDWARD M. ROBERTS, DECEASED, LATE OF ASHLAND, KENTUCKY, BY ANNIE C. ROBERTS, ADMINISTRATRIX, OF ASHLAND, KENTUCKY.

LOCOMOTIVE DIAPHRAGM AND SPARK-ARRESTER.

1,090,754.

Specification of Letters Patent. Patented Mar. 17, 1914.

Application filed February 14, 1912. Serial No. 677,477.

To all whom it may concern:

Be it known that EDWARD M. ROBERTS, late a citizen of the United States and resident of Ashland, in the county of Boyd and 5 State of Kentucky, invented certain new and useful Improvements in Locomotive Diaphragms and Spark-Arresters, of which the following is a specification.

The present invention relates to improvements in spark arresters and draft plates for locomotive boilers of the horizontal tubular type, and has for its purpose to not only improve their construction, but their general arrangement in the smoke box, 10 whereby the smoke and other gases may pass unrestricted to and out of the smoke stack, thus giving a more uniform draft to the fire and permitting a large increase of area to the exhaust nozzle, resulting in large 15 fuel economy and much greater engine efficiency.

In locomotive engines, it is the usual practice to employ a spark arrester consisting of a wire netting or a perforated plate (not 20 hooded) interposed between the tubes of the boiler and the smoke stack, by which arrangement all smoke, gases and cinders must pass through the openings to escape to the atmosphere. When these openings are in 25 any manner restricted, as by the accumulation of dirt or soot, it seriously affects the draft and proper steaming of the engine. The draft acting on the fire through the tubes is caused by the escaping steam 30 through the exhaust pipe, and the diameter of this pipe enters very materially as factor in the steaming qualities of the engine. The means for regulating this draft consists 35 usually in reducing the diameter of the exhaust pipe to increase the draft on the fire and in opening said exhaust pipe to decrease the draft, but this method is unsatisfactory since many of the locomotives of to-day are 40 laboring under a heavy back pressure caused by too small a nozzle, and this back pressure cripples the power of the engine very materially. Under the present invention, 45 however, the above disadvantages are overcome, as it permits of the employment of a very much larger exhaust nozzle than that now used, at the same time making sufficient draft for proper combustion in the fire box, and thereby cutting down the back pressure in the cylinders. The diaphragm 50 in question is provided with perforations

which conform to the shape of the flue openings, and each opening has a hood which permits of adjustment for regulating the passage of draft therethrough. And coöperating with the draft plate is a spark arrester made along precisely the same lines as the draft plate and so disposed within the smoke box with relation thereto that the cinders are prevented from escaping through the stack in incandescent condition, permitting the smoke box to keep itself clean, if desired, or trapping such a large proportion of the cinders as to make the locomotive particularly clean for passenger traffic, the advantages of which will be readily apparent.

The invention is, with respect to the draft plate, a further improvement on a similar invention disclosed in applicant's patent bearing No. 514,337, under date of February 6, 1894.

The present invention is shown in its preferred embodiment in the accompanying drawing, wherein—

Figure 1 is a vertical longitudinal section 80 on the front extension of a locomotive boiler, showing the invention installed; Fig. 2 is a front elevation thereof; Fig. 3 is a similar view looking from the line A—A; Fig. 4 is a detail section of the spark arresting plate, and Fig. 5 is a sectional view thereof, taken along the line B—B.

Referring to the several figures in further detail, and wherein like numerals of reference indicate corresponding parts in the 90 different figures shown, 1 represents the smoke box, in which is mounted the usual exhaust nozzle 2, spark arrester 3, T-head 4, and steam pipes 5, which communicate with the cylinders and are connected by the 95 T-head with the dry-pipe (not shown).

The numeral 6 represents the boiler head, in which terminate the ends of a plurality of fire tubes 7. Ordinarily, the suction produced through the fire tubes is effected in the 100 manner described in the patent specification above referred to, and which is attended by disadvantages that have been considerably overcome by the draft plate forming the basis of said patent. The present invention employs a draft plate or diaphragm 8 disposed at the proper distance in front of the fire tubes 7, upon a curved bracket 9, and being formed, as above described, with substantially semi-circular perforations 110

9 which conform with the contour of the flue openings. In the formation of the draft plate, the slitting dies which perforate the sheet, at the same time provide the hoods 10, of which there is one for each of the openings 9, said hoods being all bent downwardly and disposed substantially in the same direction. It will be obvious that, through the medium of said hoods, the openings 9 for the passage of the smoke and other gases may be enlarged or restricted, as the type of engine may require, merely by bending these hoods to or from the plate 8 as the case may be. In all other respects, 15 the structure of the draft plate 8 and its function is identical with that described in the patent above referred to and need not, therefore, be described in further detail here. In the present instance, an essential 20 feature of the draft plate lies in its position relatively to and co-operation with the spark arrester 3, as will be now explained.

The spark arrester comprises, as stated, a plate perforated with a plurality of semi-circular openings 9, the hood members 10 whereof are all disposed in a downward direction in precisely that manner shown in Fig. 1, and as explained of the hoods on the draft plate the hoods of the arrester 25 may be closed or opened with respect to their openings, whereby to permit greater or less communications through the plate as may be required. The arrester is disposed within the smoke box with its upper edge at the top 30 and near the front door thereof and is extended rearwardly and at an angle bringing its lower edge to a point within approximately two inches of the draft plate 8 and below the lower row of openings in said 35 draft plate. By this arrangement, in combination with the hooded diaphragm, the cinders are passed forward and deflected against the front part of the smoke box with a whirling motion, the succeeding ex- 40 hausts taking them out through the openings of the spark arrester. It will be noted that by this arrangement, the gases and smoke may pass unrestricted to the stack and out, which is substantially equivalent 45 to the entire removal of the customary wire netting. This gives a very decided improve-

ment in drafting the fire and permits of a large increase of area of the exhaust nozzle resulting in large fuel economy and much greater engine efficiency. The space between 55 the adjacent edges of the draft plate and the spark arrester, designated by the numeral 11, provides a sort of relief port or auxiliary opening for gases and cinders to be drawn out by the suction of the exhaust, 60 by which action the front of the smoke box cannot become charged with cinders since it is, through the medium just described, virtually self-cleaning. For access to the draft plate, the exhaust nozzle 2, or parts adjacent 65 thereto, the spark arrester 3 is horizontally divided along the line 12, the sections whereof are connected by a number of hinges 13.

What is claimed is:—

The combination with a tubular locomotive boiler having a smoke box at its forward end, the front wall of which is vertical, of a perforated draft plate disposed in front of the fire tubes of the boiler and extending forwardly and downwardly therefrom, hoods projecting downwardly from the rear face of said plate and overlying said perforations, of a perforated spark arrester secured to the top of the smoke box 75 near the front thereof and extending rearwardly and downwardly therefrom and terminating at a point near the lower edge of the draft plate, downwardly extending hoods on the forward side of and overlying 80 the perforations in the spark arrester and disposed in planes substantially parallel to the plane of the front wall of the smoke box, whereby cinders in the outer portion of the vortex developed by the flow of the 85 gases are deflected from said perforations inward to the inner portion of the vortex, to be precipitated by the latter.

The foregoing specification signed at Cat- 90 lettsburg, Kentucky, this 24th day of Janu- 95 ary, 1912.
